(57) CLAIM

The ornamental design for a flag display with storage, as shown and described.

DESCRIPTION

FIG. 1 is a front perspective view of a flag display with storage, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top view thereof;

FIG. 7 is a bottom view thereof; and,

FIG. 8 is a front perspective view of the open flag display with storage thereof.

The broken lines shown in the drawings depict portions of the article that form no part of the claimed design.
